LANDS

DISCHARGE APPARATUS

Application filed May 28, 1926, Serial No. 112,280, and in the Netherlands August 15, 1925.

This invention is based on the principle of subjecting the emission emanating from a cathode to the influence of a space charge due to an additional cathode which is disposed 5 within the same discharge tube and is so arranged relatively to the first mentioned cathode that the electrons emanating from it, in so far as they do not strike intermediate electrodes, constitute a so-called "cloud" on reversal of their direction of movement adjacent the first mentioned cathode.

If between the said two cathodes which hereinafter for convenience' sake will be referred to as "the innermost one" and "the 15 outermost one" respectively, a grid is arranged which serves as an anode for both cathodes, it can be ensured that at an increasing potential difference between the anode on the one hand and the cathode on the other 20 hand the hindering influence exercised by the space charge of the outermost cathode on the emission of the innermost one is more intense than the influence of the increase of the anode potential on the said emission. In 25 these circumstances the current flowing from the anode to the innermost cathode decreases consequently at an increasing potential difference between the said two elements so that the device can operate with a negative resistance characteristic and can be used for generating oscillations.

Preferably the device according to the invention comprises an exhausted bulb in which are concentrically arranged a central incandescent cathode, a grid-shaped anode and an enveloping cathode.

According to the invention this latter cathode is moreover preferably constructed as an equipotential cathode.

40 The invention will hereinafter be set out more clearly by reference to the diagrammatic drawing accompanying the specification.

In the said drawing:

45 Figure 1 shows diagrammatically a method of arranging the electrodes according to the invention.

Figure 2 shows in vertical section a so-called stem provided with electrodes arranged 50 as shown in Figure 1.

A central incandescent cathode 1 which is shown in the form of a wire is surrounded by an anode 2 which is perforated or otherwise provided with apertures. The said anode may consist, for example, in the manner 5 known for grids, of a helically wound metal wire as shown in Figure 2. Around the exterior of the anode 2 is mounted a second electron emitting cathode 3. The latter may consist, for example, likewise of a helically 10 wound wire heated by the passage of a current. However, it is preferable that a so-called equipotential cathode should be employed in order to prevent considerable voltage differences between the starting point and 15 the final point of the said cathode.

The electrons emanating from the cathode 3 partially pass through the anode 2 and from this moment their speed is slackened until they arrive adjacent the cathode 1 when their 20 direction of movement is reversed. Thus a continuous cloud of electrons is maintained by the cathode 3 around the cathode 1, said cloud intensifying the space charge at the cathode 1 and thus counter-acting the emission of the cathode 1. The more the cathode 25 3 emits, for example the more positive the anode 2 is relatively to the cathode 3, the greater is the extent to which this counter-action occurs apart from saturation phenomena. Now, it has been found that this 30 indirect influence of potential changes of the anode 2 on the emission of the cathode 1 can exceed the direct influence, in other words, that at an increase of the potential of the anode 2, 35 other circumstances being the same, the emission of the cathode 1 can be weakened by the increasing space charge due to the cathode 3 to a greater extent than it can be intensified 40 by the increase of the electrostatic field between the anode 2 and the cathode 1. Consequently, in a closed circuit in which the anode 2 and the cathode 1 and also a source of voltage are inserted, oscillations can be generated, as the said circuit will show a negative 45 resistance characteristic.

In the construction shown in Figure 2 the incandescent cathode 1 is stretched between two pole wires 4 which are sealed in known manner in a glass stem 5. The anode 2 con- 50

sists of a helically wound wire having its turns secured to a small carrying rod 6 which merges into supports 7 sealed in the stem 5.

The outermost cathode 3 consists of an open cylinder which is coated on its inner side with an active layer (for example an alkaline earth oxide) and which is secured in the stem 5 by a carrier 8. The heating is effected by means of a resistance wire 9 wound around the said cylinder and insulated therefrom by the insulation 14 and to which current can be supplied by wires 10 which are also led outwardly through the stem 5. The glass envelope 16 encloses the entire electrode assembly.

Obviously it is possible by regulating the temperatures of the two cathodes to intensify the effect in view by providing that at a given potential of the anode 2 a state of saturation has already occurred in the emission at the cathode 1 but not at the cathode 3. When the potential of the anode 2 increases, the direct influence of the anode 2 on the cathode 1 can be neglected and the counteracting influence of the increasing emission of the cathode 3 only remains.

Although a cylindrical and concentric arrangement of the electrodes is illustrated and described, the invention is by no means limited thereto as it is possible to indicate numerous constructions in which the hereinbefore described new principle of influencing the emission of a cathode can be realized by the space charge of one or more other cathodes.

What we claim is:

An electron discharge device comprising a source of primary electrons, a second source of primary electrons mounted concentrically about the first source, and means concentric with and intermediate these two sources of primary electrons for attracting the electrons from said sources, said means being apertured and positioned with respect to the two sources for passing electrons from one source through the apertures and thereby affecting the emission of electrons from the other source.

In testimony whereof we affix our signatures, at the city of Eindhoven, this 11th day of May, A. D. 1926.
